EXTENSIBLE STRUT FOR VEHICLE STRAIGHTENING AND REPAIR SYSTEMS

Wayne E. Hunnicutt, Big Bend, and Peter G. Rossbach, Waukesha, Wis., assignors to Applied Power Industries, Inc., Milwaukee, Wis., a corporation of Wisconsin

Filed July 15, 1968, Ser. No. 12,750

Term of patent 14 years

Int. Cl. D8—02
U.S. Cl. D41—1

FIG. 1 is a front view of an extensible strut for vehicle straightening and repair systems showing our new design; FIG. 2 is a side elevational view thereof;

FIG. 3 is a top end view thereof; and

FIG. 4 is a bottom end view thereof.

We claim:

The ornamental design for an extensible strut for vehicle straightening and repair systems, as shown.
